GEORGE C. MELROSE, OF REDONDO BEACH, CALIFORNIA.

SILENT RAILROAD-CROSSING.

1,308,719.

Specification of Letters Patent.

Patented July 1, 1919.

Application filed September 6, 1918. Serial No. 252,960.

To all whom it may concern:

Be it known that I, GEORGE C. MELROSE, a citizen of the United States, residing at Redondo Beach, in the county of Los Angeles and State of California, have invented new and useful Improvements in Silent Railroad-Crossings, of which the following is a specification.

My invention relates to silent railroad crossings, and consists of the novel features herein shown, described and claimed.

Figure 1 is a top plan view of a silent railroad crossing embodying the principles of my invention, parts being broken away and shown in section.

Fig. 2 is a fragmentary vertical sectional detail on the line 2—2 of Fig. 1.

Fig. 3 is a fragmentary vertical sectional detail at right angles to Fig. 2 and on the lines 3—3 of Figs. 1 and 2.

Fig. 4 is a fragmentary vertical sectional detail on the line 4—4 of Fig. 1.

The track of the main line 1 adjacent to the crossing comprises the rail sections 2 and 3 at one side of the crossing, the intermediate rail sections 4 and 5 in the crossing and the rail sections 6 and 7 at the other side of the crossing from the rail sections 2 and 3. The track of the crossing line 8 comprises the rail sections 9 and 10 at one side of the crossing, the intermediate rail sections 11 and 12 in the crossing, and the rail sections 13 and 14 at the other side of the crossing from the rail sections 9 and 10. The rail sections 2, 3, 4, 5, 6, 7, 9, 10, 11, 12, 13 and 14 are preferably built up by casting, forging, welding and the like to make a practically integral mass. A central pivot post 15 extends upwardly from the base 16 at the center of the square formed by the rail sections 4, 5, 11 and 12. Levers 17 and 18 are mounted through large openings 19 in the webs 20 of the rail sections 4 and 5, and placed one on top of the other upon the pivot post 15, and a pivot bolt 21 is inserted downwardly through the levers 17 and 18 and tapped into the pivot post 15. A slide-way 22 is formed at an angle of 45° across the corner which would be formed by the meeting of the rail sections 14 and 6. A tongue groove 23 extends laterally one way at the bottom of the slide-way 22. A slide rail 24 is placed on the bottom of the slide-way 22 at the opposite side from the tongue groove 23, and secured in place by screws 25, said slide rail having a tongue 26 extending into the slide-way 22.

The right angle triangular shifting rail section 27 is mounted in the slide-way 22 and has a tongue 28 extending into the tongue groove 23, and a groove 29 into which the tongue 26 extends, so as to hold the shifting section 27 from being raised out of the slide-way, and so as to allow the section to slide endwise.

A lever 30 is inserted horizontally through the opening 31 in the shifting section 27, and a pivot screw 32 is inserted upwardly through the shifting section and through the center of the lever 30 and tapped into the body of the shifting section 27, the ends of the lever 30 extending beyond the faces 33 and 34 of the section. The shifting section 27 is larger than the corner formed by the rail sections 6 and 14 would be, so that when the face 33 is in line with the inner faces 35 and 36 of the sections 4 and 6 the shifting section 27 will reach across the car wheel flange groove 37 and form a continuous rail, and so that when the shifting section 27 is moved the other way the face 34 will be in line with the faces 38 and 39 of the sections 12 and 14, and across the car wheel flange groove 40 and form a continuous rail the other way. In a like manner the right angle triangular shifting rail section 41 is mounted at the corner that would be formed by the rail sections 7 and 10, and the right angle triangular shifting rail section 42 is mounted at the corner that would be formed by the rail sections 9 and 3, and the right angle triangular shifting rail section 43 is mounted at the corner that would be formed by the rail sections 2 and 13, and a lever 44 is carried by the shifting section 41 similar to the lever 34. A similar lever 45 is carried by the shifting section 42, and a similar lever 46 is carried by the shifting section 43. The ends of the levers 30, 44, 45 and 46 are connected to the ends of the levers 17 and 18 by pivots 47, 48, 49 and 50, so that the shifting sections 27, 41, 42 and 43 will operate simultaneously. A link 51 is connected to the pivot 47. A link 52 is connected to the pivot 50 and the links 51, and 52 are connected by a pivot 53. In a like manner, a link 54 is connected to the lever 30 at the opposite end from the pivot 47 by a pivot 55. A link 56 is connected to the opposite end of the lever 44 from the pivot 48 by a pivot 57, and the links 54 and 56 are connected together by a pivot 58. A link 59 is connected to the pivot 48. A link 60 is connected to the pivot 59,

and the links 59 and 60 are connected together by pivots 61. A link 62 is connected to the opposite end of the lever 45 from the pivot 49 by a pivot 63. A link 64 is connected to the opposite end of the lever 46 from the pivot 50 by a pivot 65, and the links 62 and 64 are connected together by a pivot 66.

An actuator construction 67 is provided in combination with the rail section 14, and similar actuator constructions 68, 69, 70, 71, 72, 73 and 74 are provided in combination with the rail sections 6, 7, 10, 9, 3, 2 and 13 respectively.

15 The actuator construction 67 is shown in detail in Figs. 2 and 3. A wedge shaped actuator head 75 is mounted in the car wheel flange groove 37, said actuator head 75 having an inclined upper face 76 with its lower end pointing away from the crossing, so that when a car wheel flange approaches the crossing it will run upon the inclined face 76 and press the head 75 downwardly.

An arm 77 extends downwardly from the head 75 through a bearing 78 and the head 75 is mounted for vertical reciprocation in a housing chamber 79. A pivot 80 is mounted transversely of the rail web 81. A bell-crank lever 82 is mounted upon the pivot 80 and 30 has a slotted bearing 83 at its horizontal end, and a pin 84 fixed in the lower end of the arm 77 operates in the slot of the bearing 83, so that as the head 75 goes up and down the bell-crank lever 82 is vibrated. An 35 evener 85 is mounted horizontally transversally of the track, and one end of the evener 85 is connected to the upper end of the bell-crank lever 82. A draw bar 86 is connected to the center of the evener 85, and to pivot 53.

In a similar manner the actuator head 87 is connected to the other end of the evener 85. In a like manner the actuator heads 88 and 89 of the actuators 68 and 69 are connected to the evener 90, and the evener 90 is connected to the pivot 58, the actuator heads 91 and 92 of the actuators 70 and 71 are connected to the evener 93, and to the pivot 61, and the actuator heads 94 and 95 of the 50 actuators 72 and 73 are connected to the evener 96 and to the pivot 66.

In a practical operation, suppose that a car is moving upon the main track 1 in the direction indicated by the arrows 97 and 55 98 then the car wheel flanges in the grooves 40 and 99 will approach and pass upon the actuator heads 94 and 95, thereby depressing the heads and operating the evener 96 to move forwardly in the direction indicated 60 by the arrow 100, thereby pulling the pivot 66 forwardly and pushing through the links 64 and 62, and the levers 46 and 45 to move the right angle triangular shifting rail section 43 and 42 to bring the faces 33 into 65 line with the inner faces of the rail sections

2, 3, 4 and 5, and across the car wheel flange groove 101, and the power will be transmitted through the levers 17 and 18 to move the right angle triangular shifting rail section 27 and 41 to bring the faces 33 into line with 70 the inner faces of the rail sections 4, 5, 6 and 7, and across the car wheel flange groove 37, thereby making continuous noiseless rails for the main track 1 and for the car to pass across it. The parts will remain in this position for cars going either way upon the main line track, and until a car approaches the crossing upon the track of the crossing line 8. Then the car wheel flanges upon the crossing line going in the direction indicated 75 by the arrows 102 will strike the actuator heads 91 and 92, throw the evener 93 in the direction indicated by the arrow 103, thereby moving the right angle triangular shifting rail sections 27, 41, 42 and 43 to make a continuous track out of the crossing line 8.

It is obvious that the operation will be the same for a car coming in any one of the four directions, that no springs or counterbalances are required, that each car operates the 90 crossing for itself, and that the crossing remains in that position until moved by another car upon the other track.

Various changes may be made without departing from the spirit of my invention as 95 claimed.

I claim:

1. A silent railroad crossing comprising, track rail sections forming a crossing, there being diagonal slots across the corners 100 formed by the outside rail intersections; right angle triangular shifting rail sections slidingly mounted in the diagonal slots; two levers extending through two inside rail sections and crossing at the center of the 105 square; a fixed pivot extending through the crossed levers; second levers pivotally connected to the right angle triangular shifting rail sections and pivotally connected to the ends of the crossed levers; links pivotally 110 connected to the second levers, each pair of links being connected together; actuator heads mounted for vertical reciprocation in the car wheel flange grooves; arms extending downwardly from the actuator heads; and bell-crank levers pivotally mounted and connected to the actuator heads and connected to the links; so that when the car wheel flanges press downwardly on the actuator heads the right angle triangular shifting rail sections will be moved out of the way 115 of approaching car wheel flanges and into positions to cross the car wheel flange grooves of the other track.

2. A silent railroad crossing comprising, 125 track rail sections forming a crossing, there being diagonal slots extending clear across the corners formed by the outside rail intersections from the space between the rails of one track to the space between the rails of 130

the other track, shifting rail sections slid-
ingly mounted in the diagonal slots, two le-
vers extending under the tread portions of
two inside rail sections and crossing at the
center, a fixed pivot extending through the
crossed levers, second levers pivotally con-
nected to the shifting rail sections and pivot-
ally connected to the ends of the crossed
levers, links pivotally connected to the sec-
ond levers, each pair of links being connect-
ed together, actuator heads mounted for
vertical reciprocation in the car wheel flange
grooves, arms extending downwardly from
the actuator heads, bell-crank levers pivot-
ally mounted and connected to the actuator
heads and connected to the links, second
links connected to the shifting rail sections,
and third levers pivotally connected to the
second links and pivotally connected to-
gether and connected to the other actuator 20
heads, so that when the car wheel flanges
running upon one track press downwardly
on the actuator heads the shifting rail sec-
tions will be moved out of the way of the
approaching car wheel flanges and into po- 25
sition to cross the car wheel flange grooves
of the other track, and so that when the car
wheel flanges running upon the other track
press downwardly on actuator heads the
shifting rail sections will be again moved. 30

In testimony whereof I have signed my
name to this specification.

GEORGE C. MELROSE.
